(57) **CLAIM**

The ornamental design for a seating unit, as shown and described.

DESCRIPTION

FIG. 1 is a perspective view of a first embodiment of the seating unit;

FIG. 2 is a front elevational view thereof;

FIG. 3 is a rear elevational view thereof;

FIG. 4 is a left side elevational view thereof, the opposite side of which is a mirror image;

FIG. 5 is a top plan view thereof;

FIG. 6 is a bottom plan view thereof;

FIG. 7 is a perspective view of a second embodiment of the seating unit;

FIG. 8 is a front elevational view thereof;

FIG. 9 is a rear elevational view thereof;

FIG. 10 is a left side elevational view thereof, the opposite side of which is a mirror image;

FIG. 11 is a top plan view thereof; and,

FIG. 12 is a bottom plan view thereof.

The broken line portions of the drawings are included to show portions of the article that form no part of the claimed design.

1 Claim, 12 Drawing Sheets
